(57) **CLAIM**

The ornamental design for food dressing pliers, as shown and described.

DESCRIPTION

FIG. 1 is a right-side elevational view of a first embodiment of the food dressing pliers, the left-side elevational view (not provided) being a mirror image thereof;

FIG. 2 is a top plan view thereof, the bottom plan view (not provided) being a mirror image thereof;

FIG. 3 is a front elevational view thereof;

FIG. 4 is a rear elevational view thereof; and

FIG. 5 is a right-side, top perspective view thereof.

FIG. 6 is a right-side elevational view of a second embodiment of the food dressing pliers, the left-side elevational view (not provided) being a mirror image thereof;

FIG. 7 is a top plan view thereof;

FIG. 8 is a bottom plan view thereof;

FIG. 9 is a front elevational view thereof;

FIG. 10 is a rear elevational view thereof; and,

FIG. 11 is a left-side, top perspective view thereof.
